UNITED STATES PATENT OFFICE

102,403

DESIGN FOR A WIND POWER GENERATOR

George A. Vaughn, Newton, Iowa, assignor to
Wind-Power Manufacturing Company, New-
ton, Iowa, a corporation of Iowa

Application November 3, 1936, Serial No. 65,675

Term of patent 7 years

To all whom it may concern:

Be it known that I, George A. Vaughn, a citizen
of the United States and a resident of Newton, in
the county of Jasper and State of Iowa, have in-
vented a new, original, and ornamental Design for
a Wind Power Generator, of which the following
is a specification, reference being had to the
accompanying drawing, forming part thereof.

Figure 1 is a side elevation of a wind power gen-
erator made according to my design.

Figure 2 is an end elevation of the same, the
propellers being shown diagrammatically and one
of them being broken away.

I claim:

The ornamental design for a wind power gen-
erator substantially as shown and described.

GEORGE A. VAUGHN.
